FASTENING DEVICE

John T. Glikler, Cleveland, Ohio, assignor to Air Reduction Company, Incorporated, a corporation of New York

Application November 18, 1943, Serial No. 510,757

7 Claims. (Cl. 24—77)

This invention relates to fastening devices and particularly to a device employed in connection with the helmet and oxygen mask of an aviator to facilitate the rapid manipulation of the connection whereby the mask is held in operative position in relation to the face of the wearer. While primarily intended for the particular purpose indicated the fastening device may be used in other assemblies.

In modern high altitude aviation it is necessary for the aviator to wear a helmet and mask, the latter being connected to a source of oxygen which is supplied as required to make up the deficiency in that element which is met at higher altitudes. The mask is normally connected by a suitable strap usually of webbing to the left hand side of the helmet and a connection is provided by another strap to permit attachment to or release from the opposite side of the helmet. Thus the aviator may adjust the mask or disconnect it as may be required by the exigencies of the situation. The aviator normally will be wearing heavy gloves or mittens and his attention may be fixed upon important elements of operation of the plane or its equipment. It is, of course, imperative under such conditions that manipulation of the connection be easy, rapid and certain with a minimum of effort and attention. Connections heretofore available have not been satisfactory in these respects.

It is the object of the present invention to provide a simple and effective connecting means affording the utmost facility in manipulation so that the aviator may without close attention and almost instantaneously adjust and fasten his mask in position with assurance that it will be held securely in proper position.

Other objects and advantages of the invention will be apparent as it is better understood by reference to the following specification and the accompanying drawing in which:

Fig. 1 is a view in perspective illustrating the aviator's helmet and mask and the novel connecting means;

Fig. 2 is an enlarged fragmentary view of a portion of the helmet and mask and the fastening device a part thereof viewed in section as along line 2—2 of Fig. 3;

Fig. 3 is an elevation of the fastening device; and

Fig. 4 is a view in perspective of the improved fastening device.

Referring to the drawing 5 indicates a helmet worn by an aviator and 6 the oxygen mask which is supplied with oxygen through a tube 7. As

previously indicated the mask 6 is secured to the helmet on the left hand side by a strap (not shown) in the ordinary manner. At the right hand side of the helmet a hook 8 is secured thereto. The hook may be of any suitable material, preferably of metal. It is of sturdy construction and relatively wide.

To cooperate with the hook I provide a fastener consisting of a rectangular frame having side bars 9 and 10, end bars 11 and 12 and transverse bars 13 and 14. The frame is bent at an acute angle at the bar 13. Each of the side bars 9, 10 is thus bent to have apex portions.

A strap 15 preferably of webbing is looped about the bar 11 as indicated at 16 at one end and thus secured thereto by stitching 18. The strap is doubled and extends between the bars 12 and 14 and to a point some distance beyond the same thereby forming a stiffened tab 17 which may be stitched as indicated at 18 or otherwise treated to prevent separation of the folds. The frame as thus supported on the strap holds the bar 13 in spaced relation thereto so that it may engage the hook 8 on the helmet, the bar 13 connecting with the side bars 9, 10 at the apex portions. The bar 14 serves as means for retaining the doubled strap against the end bar 12.

The free end of the strap is looped through an adjusting buckle consisting of a frame 19 having a transverse bar 20 and a serrated end bar 21. A loop 22 is provided for connection with a strap 23 which is usually of rubber to afford resiliency and which is connected to the mask 6. The adjusting buckle permits the ready adjustment of the length of the strap 15 by the aviator to insure close fit of the mask upon his face.

When the mask is not in use it normally hangs by the strap at the left hand side of the helmet. When the aviator desires to adjust the mask in place he will grasp the tab 17 and tensioning the strap 23 will engage the bar 13 with the hook 8. This can be accomplished readily without careful attention of the elements and the aviator having a secure hold on the tab 17 can quickly move the fastener to engaging position with the hook. The mask can be disengaged as readily by simply grasping the tab 17 and with a slight pull to overcome the tension slip the bar 13 from the hook.

Various changes may be made in the detail of the construction of the device without departing from the invention or forfeiting the advantages thereof.

I claim:

1. In a quick release fastening device, a hook, a fastening element having end bars, side bars of angular shape having apex portions, spaced transverse bars extending between the side bars and intermediate of the end bars, at least one of the transverse bars being connected between the apex portions of the respective side bars to serve as the hook-engaging portion of the fastening element, and a strap secured to the end bar adjacent the one last-mentioned transverse bar and projecting between the other end bar and the transverse bar adjacent thereto to a point some distance beyond the other end bar thereby to form a tab which may be easily grasped to effect the release of the fastening element from the hook.

2. In a quick release fastening device, a hook, a fastener having end and side bars, a transverse bar extending between the side bars and intermediate of the end bars, a folded strap secured to one of the end bars and extending in double thickness to a point some distance beyond the other end bar so as to provide a tab which may be easily grasped to release the fastener from the hook, stitches extending through the double thickness of the strap to stiffen the same, means on the fastener for retaining the strap in position against the other end bar, and said transverse bar being spaced from the strap and forming a hook-engaging portion.

3. A quick-release fastening device comprising a frame member including side bars having angularly-disposed portions and a plurality of connecting transverse bars, one of the transverse bars being connected to the respective side bars adjacent the portions thereof connecting said angularly-disposed positions, said transverse bar forming a hook-engaging element, other transverse bars connecting the respective angularly-disposed portions of the side bars at opposite 40 sides of said hook-engaging element, a strap connected to one of said other transverse bars, and a tab connected to one of other said transverse bars and extending from the frame member to a position where it readily may be grasped.

4. A quick-release fastening device comprising a plate-like frame member including side bars having angularly-disposed portions connected directly to one another, and a plurality of connecting transverse bars, one of the transverse bars being connected to the side bars adjacent their apex portions, said transverse bar forming a hook-engaging element, other transverse bars connecting the respective angularly-disposed

5 portions of the side bars at opposite sides of said hook-engaging element, a strap connected to one of said other transverse bars, and a tab connected to one of other said transverse bars and extending from the frame member to a position where it readily may be grasped.

10 5. A quick-release fastening device comprising a frame member including side bars having angularly-disposed portions, and a plurality of connecting transverse bars, one of the transverse bars being connected to the respective side bars adjacent the portions thereof connecting said angularly-disposed portions, said transverse bar forming a hook-engaging element, a 15 pair of said transverse bars connecting the angularly-disposed portions of the respective side bars at one side of said hook-engaging element, at least one other of the transverse bars connecting the angularly-disposed portions of the respective side bars at the other side of said hook-engaging element, a strap connected to one of said last-mentioned transverse bars, and a tab connected to one of said last-mentioned transverse bars and extending through said pair of 20 transverse bars and beyond the frame a distance sufficient to enable it readily to be grasped.

25 6. A quick-release fastening device comprising a frame member including side members and a plurality of connecting transverse bars, a strap connected to one of said transverse bars, another of said transverse bars being located to one side of a plane passing through the transverse bar to which the strap is attached and a third transverse bar, said other transverse bar forming a hook-engaging element, and a tab connected to one of the transverse bars other than the one which forms the hook-engaging element and extending from the frame a distance sufficient to enable it readily to be grasped.

30 7. A quick-release fastening device comprising a frame member including side members and a plurality of connecting transverse bars, a strap connected to one of said transverse bars, another of said transverse bars being located to one side of a plane passing through the transverse bar to which the strap is attached and a third transverse bar, said other transverse bar forming a hook-engaging element, and a relatively stiff tab connected to one of the transverse bars other than the one which forms the hook-engaging element, said tab being of such size and extending from the frame in a direction which enables it readily to be grasped.

JOHN T. GLEKLER.
